UNITED STATES PATENT OFFICE

HARRY SWINGLEHURST, OF ORANGE, NEW JERSEY, ASSIGNOR TO SCOTT AND WILLIAMS, INC., OF NEW YORK, N. Y., A CORPORATION OF MASSACHUSETTS

SEGMENTAL CAM RING

Application filed October 7, 1929. Serial No. 398,019.

This invention deals with the construction of a segmental, multi-part ring for supporting needle cams in a circular knitting machine and is based on an idea which may be embodied either in the cylinder cam ring or in the dial cam ring often referred to as the cam cap. It provides an improved arrangement of and way of joining the several arcuate sections which make up a segment of the cam ring and an improved way of uniting adjacent segments, the objects attained being a simplification of the assembly operation and a simpler and more secure fastening together of the arcuate sections and of the segments.

15 In the accompanying drawings,

Figure 1 is a partial view in elevation of the inner face of two adjacent segments of a cylinder cam ring embodying this invention.

20 Figure 2 is a section on the line 2—2 of Figure 1 but showing a part of the base structure below the cams.

Figure 3 is a similar view, the section being on the line 3—3 of Figure 1, or in other words it is an end view of one segment, the section 25 plane being between two segments. Not all of the cams are shown in this view.

Figure 4 is a view in side elevation of part of the joint between two segments, the segments being partly broken away to show the 30 key.

Figure 5 is a top plan view of a part of a dial cam cap, showing two full segments and a third with two of the arcuate sections forming it removed.

35 Figure 6 is a view in section on the line 6—6 of Figure 5.

Figure 7 is a view in section on the line 7—7 of Figure 5 giving an end view of a segment.

Figure 8 is a partial view similar to Figure 3 showing a modification in the way of arranging a key of the sort shown in Figures 3 and 4.

Figure 9 is a partial plan view of the same modification.

45 Considering first the preferred way in which the invention is applied to the construction of a segmental ring for holding the cylinder cams, I refer to Figure 1 where are shown two of twelve segments forming a full ring. Such segments are used in a machine

having twelve yarn feeds and two types of needle, long and short, alternating about the cylinder. The cams are so arranged that the needles of one type knit at one feed while those of the other type knit at the next adjacent feed. Each ring segment carries a full set of knitting cams for effecting knitting at one yarn feed and therefore, of every two adjacent segments, one carries the knitting cams for one type of needle and the other has cams at a different level for acting on the butts of the other type of needle.

Each segment of the cam carrying ring here is built up of two equal length arcuate sections together with a base section forming part of a ring and serving as the support for the segmental sections. The base section, that is, the bottom section and the one to which the others are secured, is an integral part of the gear ring 11 by means of which the cam ring is driven. It may be noted at this point that the horizontal portion of the gear ring, the part on which the gear teeth 13 are formed, lies outside of the cam circle and that the cams are mounted on the inner face of the cam ring so as to be presented to the butts extending outwardly from the needles. The gear ring is mounted in a well known manner on the bed plate and is driven by a pinion (not shown) engaging the teeth 13. The parts of the gear ring directly involved in the built up cam segments are the upwardly extending annular flange 10 on the inner rim of the gear ring and the horizontal part 10^a of the ring just outside this flange. The parts of the ring that support one pair of arcuate sections will be referred to collectively as the base section of the segment.

The intermediate arcuate section 15 of the cam ring segment is cut away at the lower inside part in such a way that it fits against the outer side of the flange or rib 10 of the base section and presents a face above and flush with the inner face of the flange. The part 16 of the cam ring segment 15 that lies outside (that is, to the left in Figures 2 and 3) of the flange 10 is slightly higher than the flange, with the result that the weight of the intermediate section is taken by the part

10^a of the base section just outside the flange rather than by the flange itself.

It follows that the under surface 17 of this middle section at the cut away portion just clears the top of the flange.

The upper or outer section 20 of the cam ring segment is similar to the intermediate section, being cut away on its lower inside face to rest against the outer face of the intermediate section in the same way that 10 the latter fits over the flange 10, that is to say, the part that lies against the outer face of the intermediate section 15 is enough longer than the intermediate section in a vertical direction that its bottom face rests on the horizontal part 10^a of the base section and its under face 21 at the cut-away portion just clears the top of the intermediate piece 15 and imposes no strain thereon. This outer section also presents a face flush with and 20 above the inner faces of the other two sections. One or more bolts 25 extend from the outer side of the outer section through the lower parts of both the intermediate section 15 and the outer section 20 and into the flange 10, in this way securing all three sections together and securing both upper sections to the base section. The head of the bolt lies in a countersink 26, its outer end 30 lying flush with or within the outer face of the cam ring, which is the outer face of the section 20.

Certain related cam pieces are secured to each ring section according to a scheme 35 which facilitates the assembly. The base section carries all of the cams 30 which act to raise, or to limit the downward movement of, the long needles. The inner or intermediate section 15 supports the cam pieces 31 which lower, or limit the upward movement 40 of, the long needles and also the pieces which raise, or limit the downward movement of, the short needles. The cam pieces 32 which lower or hold down the short needles are 45 mounted on the third or outer ring section 20. Stating it differently, the cam pieces 30 on the base section 10 form the bottom of the cam track 33 for the long needles, those (31) on the inner or middle section 15 form the top 50 of that track and the bottom of the cam track 34 for the short needles, while the pieces on the outer section 20 complete the short needles track 34 by forming its top surface. This applies either to segment A which has 55 the knitting cams for the long needles or to segment B which holds the knitting cams for the short needles.

The arrangement of cam pieces on any one section to form a particular shape of cam track may be varied and in any event, is not 60 part of this invention. It is worthy of note however that several pieces shown here may be omitted as they serve only to limit the advancing or retraction of the needles and are 65 not part of the knitting cams proper. They

are desirable however and for that reason are shown. When therefore this description refers to cam pieces forming a track, or either surface of a track, it means the track in so far as there are definite surfaces causing, or marking a limit on, the movement of the needles. The cam pieces are held to the segment sections by screws extending through the sections from their outer sides but not beyond the latter as their heads rest in countersunk recesses.

To add to the degree of rigidity given to the segmental ring as a result of fastening the sections together by means of the screws 25, I provide keys of a particular sort set in key-ways in the adjoining end surfaces of the segments. These key-ways may enter either from the side (Figures 3 and 4) or from the top (Figures 8 and 9) and are in the part of the cam ring remote from the screws securing the sections together.

It will be understood that the sections forming the ring segments are made most easily from full rings which are cut to give the arcuate sections. Before cutting the ring from which the outer sections 20 are to be made, a series of holes are drilled, tapped and countersunk in the side face of the said ring, each hole being on the line where the cut is to be made, with the result that each end surface of a section has a large and a small semi-circular groove forming half of a countersunk tapped hole. A screw 40 forms the key to co-operate with the spline thus formed and when the sections are in place on the base section, this key is threaded into the hole formed by the two half taps in the adjoining end surfaces. The threading is primarily to hold the key in place as it is not desired to put any considerable stress on the threads.

The primary securing effected by this key comes about from the fact that the inner end surfaces 41 of the large grooves 42, formed by the countersinking described above, are beveled from their respective outer edges to their inner edges to give convex faces. The inner end surface 43 of the head of the key 40 is oppositely beveled to give a concave surface which engages the convex end faces 110 of the countersunk grooves 42 and exerts a binding force preventing separation of the segments. The same idea may be used when there is a nut forming the head with the concave surface, the nut being set in a recess 115 formed by enlarged grooves connecting with the threaded grooves and so arranged that the screw key draws it against convex end surfaces of the enlarged grooves. In Figures 8 and 9, there is shown a key 44 having the same sort of head with a concave inner face as the key 40 shown in Figures 3 and 4. There are two differences however. Here the grooves 45 forming the key way are vertical, extending from the top edge rather than 120

from the side edge of the outer section 20. The keys 44 also are different in that they have an unthreaded stem 46 beyond the threaded portion and have a close fit in a bore 47 continuous with the threaded part above. The stem 46 thus acts as a key in conjunction with the bore 47. This gives a securing function in addition to that of the co-acting beveled faces on the head of the key and the end surfaces of the large grooves.

The principal actions of such keys are to resist what may be termed bursting forces and forces tending to put the segments out of alignment. These forces are caused by needles getting bent or out of their slots in such a way as to jam against the needle cams whereby they tend to push the cam segments outwardly. This arrangement of keys in conjunction with the comparatively rigid mounting of the sections 15 and 20 on the base section gives a very satisfactory construction equivalent for practical purposes to a continuous cam ring, yet making it possible to have the desirable incidents of a sectional, segmental ring.

The assembly of the ring follows the placing of the needles of both types, long and short, in their grooves on the needle cylinder. The needles being put in from the top, their insertion is not affected by the presence of the base section with its cams 30 as the needles do not have to go below the level of these cams. Before adding the middle section 15, the long needles are pressed down onto the cams 30 of the base section and the short needles are elevated above the level of the section 15 or any of its cams 31, which are secured to it before it is put in place. This middle section is then brought up from the outside and as there are no needle butts opposite its cams there is no difficulty in locating it against the flange 10. Short retaining screws may then be inserted in holes at the side of the hole for the screw 25 and these hold the section in place while the outer section 20 is being put on. These retaining screws may be left in place as an additional securing means is desired. The outer section 20, with its cams 32 in place, is next brought against the middle section 15, but only after the short needles have been lowered into engagement with the cams 31 thereon so that they will not interfere with the cams 32 on the outer section 20. With the two sections in place on the base section, the main securing screws 25 are turned in and following that the key screws 40 are put in place, completing the assembly.

Now referring to Figs. 5, 6 and 7, it will be seen that the same scheme is utilized in building up the segments of the cam cap with only those changes made necessary or convenient by the fact that the dial cams are in a horizontal plane and the sections are

curved on the inner and outer edges rather than on their side faces. The base section here is a part of the rim of a disc 50 having a hub 51 which turns with the central spindle. Its upper surface has a cut-away part in its outer region forming two steps 52, 53 on which suitably shaped arcuate sections are placed. Both long and short needles are used on the dial, alternating about it as in the case of the cylinder needles, and every other segment carries a set of knitting cams for acting on one sort of needle while the alternate segments carry each a set of cams for the needles of the other type.

The cam 55 which advances the long needles or limits their inward movement is placed on the under side of the base section, that is, on the under side of the disc 50 near its rim, and are held by screws 57 threading in from the outer or upper surface. From this it will be seen that the part 56 of the base section forming the step 53 is a rib corresponding to the flange or rib 10 and that the end surfaces 58^a, 58^b correspond to the horizontal part 10^a in the cylinder cam base piece section. The intermediate section 60 with its cams 61, which form the outer side of the cam track 62 for the long needles and the inner side of the track 63 for the short needles, has a part cut-away which enables it to rest on the first step 53 on the outer surface of the base section 56. Unlike the corresponding parts of the cylinder section, the end face 64 formed by this cut-away part of the intermediate section rests against the rim 65 of the flange 56 and the inner end surface 66 clears the end face 58^a of the step 53.

The outer section 70 is cut to fit on the intermediate section 60 and to extend also onto the inner step 52 of the base section. It is obvious that on analogy to the cylinder segments, there could be a single step on the base section, but as the outer section 70 bears against the rim 69 of the intermediate section and the inner edge 71 of it clears the end face 58^b of the step 52, it is desirable to have some direct bearing of the outer section on the base section and here this bearing is between the lower or inner surface 72 of the outer section and the upper surface of the inner step 52. In this case, there are separate screws 75, 76 holding the outer section and the intermediate section to the base section. As in the cylinder segments, the outer section carries the cam pieces 77 which either retract, or limit the advance of, the short needles and form the outer side of the cam track 63 for the short needles.

The assembly is effected in the same manner as that for the cylinder segments, the sections being brought up from the outer side toward the needles, with their cams in place and after the needles have been so set as to avoid interference with the cams.

The key means between segments are similar also, but the holes 80 or pairs of semi-circular slots are longer and are tapped only at their outer ends 81. The keys are correspondingly threaded at their outer ends 82 and the unthreaded shanks 83 of the keys fit closely in the holes 80 formed by the semi-circular slots. The key action therefore is between the unthreaded parts of the keys and key-ways and the threaded parts serve to hold the keys in place. The principal difference between the keys used in the cap and those in the cylinder ring is that the latter rely principally on the co-acting beveled faces to hold the segments in alignment.

It is possible to vary many of the details of the construction described and shown here and it therefore is the intent to include within the fair scope of the following claims all constructions embodying the inventive thoughts therein set forth.

I claim:

1. A needle cam ring segment comprising a base section with a rib presenting an inner face, an intermediate section resting against the outer face of said rib and presenting a face flush with the inner face thereof, and a third section resting against the outer face of the intermediate section and presenting a face flush with the inner face of the rib, said sections being adapted to support needle cams, and means for securing said intermediate and said third section to the base section.
2. A needle cam ring comprising a member with an annular rib, an arcuate section resting against the outer face of said rib and presenting a face flush with the inner face thereof, and a third arcuate section resting against the outer face of said section and presenting a face flush with the inner face thereof, said rib and sections being adapted to carry needle cams on their inner faces, in combination with means securing said two sections to the rib.
3. A needle cam ring comprising a member with an annular rib, a series of arcuate sections resting against the outer face of said rib and each presenting a face flush with the inner face of said rib, a second series of sections resting against the outer faces of said first series and each presenting a face flush with the inner face of said rib, said rib and said section being adapted to carry needle cams on their inner faces, in combination with means securing said section to said rib, and key means between adjoining sections.
4. A needle cam ring segment comprising a base section, an intermediate section resting against the base section and an outer section against the intermediate section, all three presenting inner faces flush with one another and carrying cams for co-operation with long and short needles, the base section carrying the cams forming one side of the cam track

for one type of needle, the intermediate section carrying the cams forming the other side of that track and also one side of the track for the other needles, and the outer section carrying the cams for the other side of the second track.

5. In a segmental cam ring, semi-circular grooves in adjoining faces of two segments, forming a key-way, and a key for co-operation therewith, said key and key-way being threaded and screwed together for a part of their length.

6. In a segmental cam ring, two segments having in adjoining faces semi-circular grooves together with enlarged semi-circular recesses connecting with said grooves and providing convex end surfaces, in combination with a threaded member for reception in said grooves and a head adapted to be drawn against said end surface by said member, said head having a concave end surface for engaging the said convex surface.

7. In a segmental cam ring, two segments having in adjoining faces grooves, forming together a threaded recess with a convex end surface, in combination with a threaded key having a concave end surface with its concave surface engaging said convex surface.

8. In a segmental cam ring, two segments having in adjoining faces grooves, forming together a threaded recess, in combination with a threaded key, said key and recess having co-operating beveled faces holding said segments together.

In testimony whereof I have signed my name to this specification.

HARRY SWINGLEHURST.
